BINDING MACHINE COMPANY, OF BOSTON, MASSACHUSETTS, A CORPORA-
TION OF MAINE.

STRIP-SERVING DEVICE.

1,150,802.

Specification of Letters Patent. Patented Aug. 17, 1915.

Application filed October 19, 1907. Serial No. 398,245.

To all whom it may concern:

Be it known that I, FREDERICK S. ANABLE, a citizen of the United States, residing at Boston, in the county of Suffolk, State of Massachusetts, have invented an Improvement 5 in Strip-Serving Devices, of which the following description, in connection with the accompanying drawings, is a specification, like letters on the drawings representing like parts.

This invention relates to devices or apparatus for supplying strips of paper or the like employed for wrapping or binding packages or for use as labels of any desired 15 length, and has particular reference to that type of apparatus employing a support for a coil of paper strip previously gummed and then dried, and having provisions for moistening the gum upon the strip as the latter is drawn from its coil. It is apparent 20 that an unguammed strip of paper or the like may be employed, in which case the moistening device for the strip suitably positioned with respect thereto would contain 25 an adhesive instead of water.

In order that the principles of my invention may be readily understood, I have disclosed a single type or embodiment thereof in the accompanying drawings, wherein—

Figure 1 is a side elevation of a strip serving apparatus constructed in accordance with my invention; Fig. 2 is an end elevation of the apparatus shown in Fig. 1 with a portion of the wall of the tank or reser- 30 voir removed; Fig. 3 is a side elevation of another form of my invention; Fig. 4 is an end elevation of the construction shown in Fig. 3, a portion of the walls of both reser- 35 voirs being broken away; Fig. 5 is a side elevation of a portion of a strip serving apparatus embodying another form of my invention; Fig. 6 is a side elevation, par- 40 tially broken away, of a portion of a strip serving apparatus embodying still another 45 form of my invention; Fig. 7 is an end elevation, partially broken away, of the form of apparatus represented in Fig. 6; Fig. 8 is a plan view of a portion of the apparatus shown in Fig. 6; Fig. 9 is a side elevation 50 of still another form of my invention; Fig. 10 is a plan view of a portion of the appa- 55 ratus shown in Fig. 9; Fig. 11 is a trans- 60 verse, vertical section upon the line 11—11 of Fig. 10; Fig. 12 is a similar section upon the line 12—12 of Fig. 10; Fig. 13 is a 55 similar section upon the line 13—13 of Fig. 10.

Strips of paper in rolls having an adhesive upon one side have been extensively employed for a few years past as a substi- 60 tute for string in securing packages and the like and have been found effective for the purpose. A strip so prepared is, however, necessarily wrapped about the package exteriorly, and its use is therefore restricted. 65 I contemplate the use of a strip of any suitable material having an adhesive applied to both surfaces thereof. Such a strip is susceptible of a wide range of uses to which a strip having an adhesive upon one 70 surface only is not applicable. A strip such as I contemplate using may be employed to unite sheets of material throughout their entire extent or overlapping portions of such material so that continuous lengths of 75 such material may be thus provided. Such a strip may be also employed in securing packages having one or more ends of the wrapper overlapped onto the body thereof. One surface of the strip such as I contem- 80 plate using may be adhesively applied to the body of the wrapper directly beneath the overlapping end which may then be folded down upon and adhesively applied to the other face of the strip. A package may 85 be secured in this manner, and yet the securing means may remain entirely concealed and be thoroughly protected from rough usage. Thus, not only is the package 90 more strongly secured but the appearance thereof is enhanced. Obviously, packages wrapped in artistically prepared wrappers may be secured in this manner without in any way impairing the appearance of the wrapper. Many mercantile houses employ 95 distinctive wrappers which have become so well known as to have something the value of a trade-mark. A securing strip such as I have above described may be employed with such a special wrapper, being quickly 100 applied thereto and yet being wholly concealed so that such specially prepared wrapper presents an uninterrupted and attractive appearance. Furthermore, such a strip may

be more effectively employed than sealing wax, inasmuch as it does not crack or crumble and is thoroughly protected from rough usage. These are but a few of the many 5 novel uses to which such a strip may be put.

In this application I have disclosed and 10 claimed several forms of apparatus by which a strip so prepared may be suitably moistened upon both sides thereof. It is apparent, however, that if the strip be not previously provided with an adhesive upon opposite surfaces, I may replace the moisteners by suitable adhesive applying means.

Referring more particularly to the drawings and first to the form of my invention disclosed in Figs. 1 and 2, the framing of the apparatus is represented at 1, it being of any suitable form, material and construction. Suitably mounted thereon is a casing 2 wherein the strip, preferably in the form of a coil or roll, is mounted as upon a spindle. Tension may, if desired, be imparted in any suitable manner to the strip, as by means of a screw 3 or the like mounted upon 25 the spindle supporting the coil or roll. Suitably mounted in operative relation to the casing 2 is a tank or reservoir 4 adapted to contain water, or a suitable adhesive in case a non-gummed strip is employed. 30 While any suitable moistener may be employed in connection with the tank 4, preferably I employ a roll 5 loosely mounted at one end of a lever 6 pivoted at 7 in the walls of the tank and having the opposite 35 end thereof positioned in the path of the paper as it issues from the casing 2. If desired a roll 8 may be loosely mounted upon said end of the lever. It is apparent that when the strip 9 is drawn upon for 40 use the end of the lever that is in contact with the strip is depressed, thereby elevating the roll 5 into contact with the strip to moisten the lower face thereof. When the strip is not drawn upon for use, it is 45 desirable that the free end thereof should not be in contact with the moistener or moisteners. Any suitable means may be employed to prevent such contact, located in advance of the moistening point or in the 50 rear thereof. Preferably, however, I employ means positioned in the rear of the moistening point and herein to that end I have mounted upon the pivot 7 of the lever 6 a resilient wire 9' which, when the 55 moistener 5 is in the position indicated in Fig. 1, supports the free end of the strip above the moistener and which, when the strip is drawn upon for use, yields to permit the effective engagement of the moistener 5 and the strip 9. Any suitable means 60 may be employed to moisten the opposite face of the strip. Preferably, however, I employ means to moisten both faces simultaneously. In this form of my invention, I 65 employ a strip 10 preferably formed as a

wicking, the ends whereof are immersed in the water or adhesive of the tank 4, and the intermediate portion whereof extends in substantial parallelism with the surface of the moistener 5 and is sufficiently spaced 70 therefrom to permit the free end of the strip 9 to be out of contact with both moisteners when the strip is not drawn upon for use. That is to say, the moistener 10 in this form of the invention is of a general inverted U- 75 shape, being supported in any suitable manner. Preferably, the upper portion 11 of the tank or reservoir forms a suitable backing for the second moistener. It will be apparent that as the strip 9 is drawn upon 80 for use, the lower moistener 5 is lifted into engagement with the strip and lifts the same into engagement with the upper moistener 10, whereby both surfaces of the strip are moistened for use. Any suitable severing means may be employed. Herein for the purpose, I have indicated a blade 12 formed upon the forward portion of the tank or reservoir 4 at the upper face thereof, so that after the desired length of strip 90 has been drawn from the roll the operator may readily draw the strip against the blade and sever the length drawn.

In Figs. 3 and 4, I have indicated a second form of my invention wherein the base 95 1 and the casing 2 may be of any suitable construction. In this form of the invention I provide a lower tank or reservoir 13 and an upper tank or reservoir 14, within which any suitable moistening devices may 100 be mounted. Herein I have shown mounted within the tank 13 a roll 15 having any suitable moistening surface and preferably mounted for free rotation upon the end of a lever 16 that is pivoted at 17 upon 105 a suitable projection 18 extending from the tank 13. The opposite end of the lever 16 is extended into the path of the strip 19 as it issues from the casing 2, and preferably is provided with a loose roll 20 from which 110 the strip passes in use. Preferably, a resilient wire 21 is mounted in any suitable manner, as upon the tank, it acting to support the free end of the strip 19 from contact with the moistener 15 when the strip is not 115 drawn upon for use but yielding to permit effective engagement of the strip and moistener when the former is drawn upon. The tank 14 may be supported in any suitable manner so as to moisten the opposite surface of the strip. It is apparent that if two tanks be employed, they may be mounted as shown or in any other manner as, for example, side by side with space between them 120 for the passage of the strip, in which event the roll of strip may be supported in a vertical or a horizontal position. If a tank, such as indicated at 14, be employed mounted above the strip, means should be provided 125 to prevent leakage of the water onto the 130

strip. The reservoir should preferably be of sufficient capacity to contain water sufficient for a considerable period. I have not deemed it necessary, in this form of the invention, to illustrate reservoirs of much capacity, inasmuch as it is apparent that this is within the province of those skilled in the art. Preferably I employ absorbent pads, such as indicated at 22 and 23, the lowermost 10 whereof is supported upon any suitable ledge in the tank, and through which pads the water passes as they become saturated. If desired, I may interpose between such pads and below pad 23 strips of wire mesh 15 as indicated at 24 and above the uppermost pad a perforated plate 25. Any desired arrangement of pads, plate and wire mesh strips may be employed. Beneath the lowermost pad is mounted preferably for free 20 rotation a roll 26 having an absorbent surface. The tank 14 should be preferably so shaped at the lower end thereof as quite closely to engage the surface of the roll 26 and yet not so as to prevent free rotation 25 thereof. In this manner, dripping of the water from the reservoir is prevented. It is apparent that as the strip 19 is drawn upon for use the roll 15 is raised into engagement with the strip and elevates the same into contact with the upper moistener 30 26, so that both surfaces of the strip are simultaneously moistened. Any suitable severing device may be employed. For the purpose I have herein indicated a blade 27 35 mounted upon the forward face of the upper reservoir 14, so that after the desired length of strip has been drawn from the roll the operator may readily sever the same. It is apparent that in case I employ an upper 40 reservoir I may mount any suitable moistener therein as, for example, a stationary wicking. I prefer, however, to employ a roll that may freely travel as the strip is drawn past the same.

45 In Fig. 5, I have indicated another form of my invention, wherein lower and upper tanks 28 and 29 may be employed similar to the tanks shown in Fig. 3. In such form of the invention, however, I have provided 50 means whereby, when the strip is drawn upon for use, both the upper and lower moisteners may be thereby moved into effective engagement with the strip. To this end, any suitable construction may be employed. Herein, for the purpose, I have indicated a lower roll 30 loosely mounted upon the lever 31 pivoted upon a projection 32, the opposite arm of the lever extending into the path of the strip 33 and preferably having thereon a roll 34, over which the strip passes. Suitably mounted in the framing, as upon an extension 35 of the projection 32, is a lever 36 having loosely mounted upon the free end thereof a roll 37. In order that 55 the draft upon the strip serving to elevate the moistener roll 30 may depress the moistener roll 37, a link 38 is provided, a spring 39 being employed to return the moistener roll 37 into its retracted position in contact with the lower absorbent pad 23, which may 60 be similar to that shown in Fig. 3. Any suitable severing means may be employed. Herein for the purpose I have mounted upon the forward face of the upper tank 29 a blade 40, against which the strip may be 65 deflected after the proper length has been drawn from the roll.

70 In Figs. 6, 7 and 8, I have indicated still another form of my invention, wherein I have provided two tanks located side by side 80 with a space between them for the passage of the strip. It is apparent that in this form of the invention the roll of paper may be supported vertically as shown or horizontally and that the two tanks may be suitably disposed in accordance with the preferred arrangement of the roll. Herein upon a suitable portion 41 of the framing are provided tanks 42 and 43 adapted to receive therein moisteners of any desired type. 85 Preferably, however, I provide in the tank 43 a roll 44 loosely mounted upon its bearings so as to rotate when the strip is drawn upon for use, such roll being covered with a suitable absorbent material. The front 45 of 90 such tank is provided with an opening therein to expose a portion of the roll 44 to permit contact therewith of the strip 46. Pivoted upon the tank 42 is a lever 47 having 95 preferably loosely mounted upon one end thereof a roll 48, the periphery thereof being provided with a suitable absorbent material. The opposite arm of the lever 47 extends into the path of travel of the strip 46 and is 100 preferably provided with a loosely rotating roll 49. A coil spring 50 connected to the tank 42 and the lever 47 tends normally to withdraw the roll 48 into the tank 42. The face of the tank 42 adjacent the tank 43 is 105 provided with an opening 51. It is apparent that when the strip 46 is drawn upon for use, the roll 48 is projected through the opening 51 of the tank 42 into engagement with the strip 46 and that the strip is thereby pressed into contact with the roll 44 so 110 that both surfaces of the strip are moistened. Any suitable means may be employed to sever the strip. Herein for the purpose, I have indicated a severing blade 52 suitably mounted upon the upper portion of the tank 42. The extremity 53 of the strip 46 should be freely accessible to the operator. In order to support such extremity clear of the blade 52, I have herein provided a light wire loop 54, to the ends whereof coil springs 55 and 56 are connected, the other ends of said 115 springs being suitably attached to any convenient part of the framing. It is apparent that when the strip is deflected to be severed by the blade 52 the wire loop 54 yields, but 120

125 65 the draft upon the strip serving to elevate 130

that after the strip has been severed the springs 55 and 56 return the wire loop to the position indicated in Figs. 6 and 8, thus positioning the extremity of the strip so as to be readily accessible.

In Figs. 9 to 13 inclusive is represented still another form of my invention wherein instead of applying an adhesive to both surfaces of the strip, I apply the adhesive, such as a suitable gum, to but one surface thereof and then fold the strip upon itself so that the portions of the strip having no adhesive applied thereto are in contact. Thereafter, I suitably moisten the exposed surfaces of the folded strip. Thus, although adhesive is applied to but one surface, I secure the advantages of a strip having an adhesive applied to both surfaces by folding the same upon itself with the adhesive surface outward. It is apparent that the strip may be so folded in any suitable manner. Preferably, however, I prefer to fold the strip longitudinally. If desired, the folding may be such that the meeting edges may slightly overlap but preferably the folded edges merely meet without overlapping. Any suitable mechanism may be employed to fold the strip for the purpose stated. Herein, for the purpose, I mount upon a suitable standard 59 a former composed of opposing members 60 and 61 removably connected together in any suitable manner as by screws 62. If desired, a guide 63 may be provided at the free end of the former to receive the strip 64 delivered from the casing 2. The members of the former are so constructed that the strip may be fed to the entrance thereof in a flat condition and by successive stages folded to the desired extent. Preferably the former is so constructed that the opposite edges of the strip are turned downwardly and to this end I provide suitable grooves 65 and 66 in the member 60 merging at their upper ends into the transverse groove 67 in the upper member 61, the grooves 65 and 66 being gradually inclined inward to an increasing extent toward the exit. It is apparent that the edges of the strip may be folded inwardly until substantially parallel with the central portion of the strip but preferably the strip issues from the former with the opposite edges deflected inwardly at a suitable angle, as indicated at 68 in Fig. 9, the strip then passing through suitable presser rolls 69 and 70, one of said rolls and herein the upper one being yieldingly mounted in its bearings and positioned by means of springs 71. It is apparent that the strip may be delivered from the casing 2, either by draft upon the strip by the operator or by feeding means, the former construction being indicated in this type of the invention. In advance of the former is provided a suitable moistener for the opposite surfaces of the strip, herein represented as

a tank 72 having therein a moistener roll 73 provided with a suitable absorbent surface and preferably loosely mounted upon a lever 74, the opposite end whereof is provided with a roll 75 extending into the path of travel of the strip 64, whereby, when the latter is drawn upon, the roll 75 is depressed and the moistener 73 is elevated into contact with the lower surface of the strip and lifts the upper surface thereof into contact with the upper moistener 76, which may be of any suitable construction, as, for example, that represented in Figs. 1 and 2. If desired, suitable means may be employed tending to elevate the strip when it is not drawn upon. To that end, I may employ a spring lifter 77 formed as a wire loop, the opposite ends whereof are coiled about the shaft of the lever 74. If desired, any suitable guide may be employed to prevent contact of the strip with the upper moistener when the strip is not drawn upon. Any suitable severing means may be employed in this form of my invention. Herein I have indicated a severing blade 78 mounted upon the upper portion of the tank, against which the strip may be deflected after the proper length has been drawn from the casing 2.

Having thus described one type or embodiment of my invention, I desire it to be understood that although specific terms are employed, they are used in a generic and descriptive sense and not for purposes of limitation, the scope of the invention being set forth in the following claims.

Claims:

1. A strip serving apparatus comprising a strip support, a tank or reservoir, a moistener located in operative relation thereto and adapted to moisten one surface of the strip and a second moistener adapted to moisten the opposite surface of the strip, one at least of said moisteners being bodily movable out of strip moistening relation.

2. A strip serving apparatus comprising a strip support from which a strip may be delivered for use, means for simultaneously moistening both surfaces of the strip, and means whereby at least one face of the strip is maintained from contact with the moistening means when the strip is not drawn upon for use.

3. A strip serving apparatus comprising a strip support, a tank or reservoir, a moistener mounted in operative relation thereto, means operated by draft upon the strip by the operator to move said moistener into contact with one surface of the strip to moisten the same, and means to moisten the opposite surface of the strip.

4. A strip serving apparatus comprising a strip support, a tank or reservoir, a moistener mounted in operative relation thereto, means operated by draft upon the strip to move said moistener and strip relatively to

and into engagement with each other, and means to moisten the opposite surface of the strip.

5. A strip serving apparatus comprising a strip support, tanks or reservoirs located in operative relation thereto, two moisteners located in operative relation to said tanks or reservoirs and adapted respectively to moisten the two surfaces of the strip, one at least 10 of said moisteners having a surface adapted to travel with the strip during the moistening operation.

6. A strip serving apparatus comprising a strip support, two tanks or reservoirs, a 15 moistener mounted in operative relation to each tank or reservoir and adapted respectively to moisten the two surfaces of the strip, said moisteners having surfaces adapted to travel with the strip during the moistening thereof.

7. A strip serving apparatus comprising a strip support, two tanks or reservoirs mounted in operative relation thereto, a roll 25 mounted in each tank or reservoir and adapted to moisten the opposite surfaces of the strip, and means to move one of said rolls into engagement with said strip.

8. A strip serving apparatus comprising a strip support, moistening means located in 30 operative relation to said support and having provisions for moistening both surfaces of the strip, and means whereby the strip and the moistening means are out of contact when the strip is not drawn upon for use.

35 9. A strip serving apparatus comprising a strip support, moistening means mounted in operative relation to said support adapted to moisten both surfaces of the strip, and means for maintaining the strip out of contact with the moistening means when not drawn upon for use.

40 10. A strip serving apparatus comprising a strip support, moistening means mounted in operative relation to said support adapted to moisten both surfaces of the strip, means for maintaining the strip out of contact with the moistening means when not drawn upon for use, and strip severing means.

45 11. A strip serving apparatus comprising a strip support, moistening means mounted in operative relation to said strip support and adapted to moisten both surfaces of the strip, the construction and relation of the parts being such that when the apparatus is 50 in use both surfaces of the strip may be moistened by said moistening means, and means for maintaining both surfaces of the strip out of moistening relation to said moistening means when the apparatus is not in use.

55 12. A strip serving apparatus comprising a strip support, moisture holding means, moisture receiving means positioned in operative relation to said moisture holding means and adapted to contact with both sur-

faces of the strip when the apparatus is in use, and means for maintaining both surfaces of the strip out of contact with said moisture receiving means when the apparatus is not in use.

70

13. A strip serving apparatus comprising a strip support, and moistening means for opposite faces of the strip, and means whereby one at least of the faces of the strip is supported out of contact with the moistening means when the strip is not drawn upon for use.

75

14. A strip serving apparatus comprising a strip support, strip moistening means, strip severing means so positioned that the free end of the strip when in its service path is adjacent thereto, and means tending normally to move the free end of the strip from the severing means.

80

15. A strip serving apparatus comprising a strip support, strip moistening means, strip severing means, and means normally preventing contact of the free end of the strip with the severing means.

85

16. A strip serving apparatus comprising a strip support, strip moistening means, strip severing means, and a spring device normally preventing contact of the free end of the strip with the severing means.

90

17. A strip serving apparatus comprising a strip support, strip moistening means, strip severing means so positioned that the free end of the strip when in its service path is adjacent thereto, and yielding means to withdraw the free end of the strip from the severing means.

95

18. A strip serving apparatus comprising in combination a strip support, strip moistening means, strip severing means, and a movable device adjacent the severing means 100 and acting by its movement to move the free end of the strip away therefrom.

105

19. A strip serving apparatus comprising a strip support, from which a strip may be delivered for use, means for moistening 110 both surfaces of the strip during the serving thereof, and means whereby at least one face of the strip is maintained from contact with the moistening means when the strip is not drawn upon for use.

115

20. A strip serving apparatus comprising a strip support, a strip moistener and a strip severer both in substantially the normal service path of the strip, whereby the strip may be severed without substantial deflection from its service path, and means tending to deflect the free severed end of the strip from the strip severer.

120

21. A strip serving apparatus comprising a strip support, strip moistening means, 125 strip severing means so positioned with respect to the service path of the strip that the free end of the strip when in its service path is adjacent thereto, and yielding means engaging the strip closely adjacent said 130

severing means to withdraw said free end of the strip from said severing means.

22. A strip serving apparatus comprising in combination a strip support, a pair of moisteners arranged at opposite sides of the service path of the strip, means for supporting one of said moisteners out of the service path of the strip, means dependent upon strip service to move said moistener into moistening relation to the strip, a strip severing blade between said moisteners, and yielding means adjacent the free end of the strip tending normally to withdraw the free end of the strip from contact with said severing blade.
23. A strip serving apparatus comprising a strip support, strip moistening means for both surfaces of the strip, strip severing means so positioned with respect to the service path of the strip that the free end of the strip when in its service path is adjacent thereto, and means coöperating with the tip end of the strip to withdraw said tip end from said severing means after strip severance.
24. A strip serving apparatus comprising a strip support, strip moistening means,

means relatively to move the strip and the moistener by draft upon the strip, strip severing means so positioned with respect 30 to the service path of the strip that the free end of the strip when in its service path is adjacent to said free end of the strip, and a device engaging the tip end of the strip adjacent said severing means to withdraw 35 said tip end of the strip from said severing means.

25. A strip serving apparatus comprising a strip support, strip moistening means, strip severing means, and yielding means 40 normally preventing contact of the free end of the strip with the strip severing means.

26. A strip serving apparatus comprising a strip support, strip moistening means, strip severing means, and movable means 45 normally preventing contact of the free end of the strip with the strip severing means.

In testimony whereof, I have signed my name to this specification, in the presence of two subscribing witnesses.

FREDERICK S. ANABLE.
